UNITED STATES PATENT OFFICE

158,198

FINGER RING

Ersel F. Kirkwood and Sidney L. Stevens,
Salem, Oreg.

Application November 15, 1948, Serial No. 149,632

Term of patent 14 years

(Cl. D45—10)

To all whom it may concern:

Be it known that we, Ersel F. Kirkwood and Sidney L. Stevens, both citizens of the United States, and both residing in Salem, in the county of Marion and State of Oregon, have invented a new, original, and ornamental Design for Finger Rings, of which the following is a specification, reference being had to the accompanying drawing, forming part thereof.

Fig. 1 is a top plan view of a finger ring, showing our new design.

Fig. 2 is a side elevation, and

Fig. 3 is an end elevation of the same.

We claim:

The ornamental design for a finger ring, substantially as shown.

ERSEL F. KIRKWOOD.
SIDNEY L. STEVENS.
